US0D1110453S

(12) **United States Design Patent** (10) **Patent No.:** **US D1,110,453 S**
(45) **Date of Patent:** **** Jan. 27, 2026**

(54) **SHROUD**

(71) Applicant: **GOLFTEC ENTERPRISES LLC**, Englewood, CO (US)

(72) Inventors: **Don Thorup**, Englewood, CO (US); **Rahim Stennett**, Englewood, CO (US)

(73) Assignee: **Golftec Enterprises LLC**, Englewood, CO (US)

(**) Term: **15 Years**

(21) Appl. No.: **29/945,323**

(22) Filed: **Jun. 3, 2024**

(51) **LOC (15) Cl.** **21-02**

(52) **U.S. Cl.**

USPC **D21/791**; D21/696

(58) **Field of Classification Search**

USPC D21/662, 692, 693, 694, 696, 791

CPC A63B 21/063; A63B 21/154; A63B 21/00058; A63B 21/0632; A63B 21/155; A63B 2071/009

(57) **CLAIM**

The ornamental design for the shroud as shown and described.

DESCRIPTION

FIG. 1 shows a front perspective view of a shroud; FIG. 2 shows a rear perspective view of the shroud of FIG. 1;

FIG. 3 shows a front view of the shroud of FIG. 1;

FIG. 4 shows a rear side view of the shroud of FIG. 1;

FIG. 5 shows a left side view of the shroud of FIG. 1;

FIG. 6 shows a right view of the shroud of FIG. 1;

FIG. 7 shows a top view of shroud of FIG. 1; and,

FIG. 8 shows a bottom view of shroud of FIG. 1.

When used in the drawings the broken lines represent an environment of use and form no part of the claim. The dot-dash-dot lines depict a boundary of the claim and form no part of the claim.

1 Claim, 6 Drawing Sheets
